CLAIM

I claim the ornamental design for a chair, as shown and described.

DESCRIPTION

FIG. 1 is a perspective view showing the chair of my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed dot dashed lines in FIG. 7 define the bounds of the claim and form no part of the claimed design. The even dashed lines in FIGS. 1-7 show stitching which forms the claimed design.
